(57) **CLAIM**

I claim, the ornamental design for a cannula tip, as shown and described.

DESCRIPTION

FIG. 1 is a front, top, and, right-side perspective view of a cannula tip, showing the claimed design;

FIG. 2 is a front view thereof;

FIG. 3 is a back view thereof;

FIG. 4 is a left side view thereof;

FIG. 5 is a right side view thereof;

FIG. 6 is an enlarged top view thereof;

FIG. 7 is an enlarged bottom view thereof;

FIG. 8 is an enlarged view along line 8 as shown in FIG. 1; and,

FIG. 9 is an enlarged view along line 9 as shown in FIG. 1. The evenly spaced broken lines shown in FIGS. 1–5, 7, and 9 depict parts of the cannula tip and form no part of the claimed design.
